UNITED STATES PATENT OFFICE.

AUGUST CELUS, OF MOLINE, ILLINOIS.

PUZZLE.

1,105,878.

Specification of Letters Patent.

Patented Aug. 4, 1914.

Application filed December 7, 1911. Serial No. 664,338.

To all whom it may concern:

Be it known that I, AUGUST CELUS, a citizen of the United States, and a resident of Moline, in the county of Rock Island and 5 State of Illinois, have invented certain new and useful Improvements in Puzzles, of which the following is a specification, reference being had to the accompanying drawings.

10 This invention has relation to certain new and useful improvements in puzzles; and the object of my invention is to provide an entertaining advertising novelty including a string or other pliable member having its 15 ends tied to form two terminal loops and two similar folded sheets, each having both its ends apertured. The string is drawn through the apertures and then in a certain manner the terminal loops are placed about 20 the folded sheets between the ends thereof, the trick then being to remove the string after having been secured in a manner peculiar 25 to my puzzle, without untying the loops or cutting the string.

With these and other objects in view the 30 present invention consists in the combination and arrangement of parts as will be hereinafter more fully described and finally pointed out in the appended claim, it being 35 further understood that changes in the specific structure shown and described may be made within the scope of the claim, without departing from the spirit of the invention.

In the accompanying drawings forming a 40 part of this specification and in which like numerals of reference indicate similar parts in the several views: Figure 1, shows a face view of an advertising novelty constructed according to my invention. Fig. 2, shows 45 an edge view with the members in a folded condition. Fig. 3, shows one of the members flattened out. Fig. 4, shows the opposite side of the flattened out member. Fig. 5, is a perspective view of a modification of 50 my puzzle. Fig. 6, shows the first step in removing one of the blocks. Fig. 7, shows the second step in removing a block. Fig. 8, shows the manner of releasing the loop. Fig. 9, shows one of the loops drawn out of 55 the first aperture.

In my present invention I provide a puzzle arranged to be used as an advertising novelty, including a string and two folded sheets of paper which are arranged to receive the advertising matter upon both sides.

In the drawing two sheets of paper are

shown, each of which is folded three times, but it should be understood that the sheets may be folded twice or more than three times if desired. One of the members has 60 the folds or sections marked 10, 11, and 12, while the opposite member has its folds or sections marked 13, 14 and 15. Each fold has its ends apertured, the series of apertures at one end within the folds 10, 11 and 65 12 being marked 3', and within the opposite end 4'. To add to the attractiveness of the sheet, the ends 2' are shown as rounded. The openings within the folds 13, 14 and 15 are marked 5' and 6', and employed in connection with these two folded members, 70 which may be in the form of sheets of paper, card-board, celluloid, fabrics or the like, is a string 16. This string has its ends tied to form the terminal loops 17 and 18. 75 This string is secured to the folded sheets in a peculiar manner after the sheets have been folded, as shown in Fig. 2 for instance.

In Figs. 5, 6, 7, 8 and 9, I show a modification where I employ two flat rigid members 80 4 and 5, preferably in the form of wooden blocks, or if desired these members may be made of celluloid or other suitable material. As shown, these rigid members 4 and 5 are of similar construction, each having an 85 aperture at each end, these apertures for the sake of convenience being marked 6 and 6', the apertures 6 being termed the outer apertures and the apertures 6' being referred to as the inner apertures. Where the flat 90 folded sheets are used, these are provided with printing or suitable advertising matter upon both faces. One of the members is then folded. The string 16 is then drawn through the inner apertures 4' and 5' in such 95 a manner that the loops 17 and 18 encompass the folded members at a point between the ends thereof, an intermediate portion of the string extending over one face of each member, as shown in Figs. 1 and 2. And 100 these last mentioned figures show the members in flat or folded condition, while Figs. 3 and 4 show how the string is drawn out when it is desired to flatten out the folds in reading the advertising matter thereon. 105 The employment of the folds further tends to add apparently to the mystery of the puzzle.

The trick is to remove the string 16 from the two folded members. The method of removing the string is best shown in Figs. 6, 7, 8 and 9, where a thong 1 is used in con-

nection with the rigid members 4 and 5. The first step is to draw the string portion between the two apertures outward to increase its length, as shown in Fig. 6, so that 5 the terminal loop may be drawn through the inner aperture 6' or the apertures 4' where the paper members are used, in the manner shown in Fig. 7. The opposite member as the one marked 5 in Fig. 8, is then carried 10 through the loop 2 in the manner shown in Fig. 8. After the member 5 has been carried through the loop 2, the loop can be easily drawn out of the inner opening, as the one marked 6' in Fig. 9, after which the 15 string or thong is readily drawn out of both of the end openings. The string or thong is secured in repeating the operation backward, as shown in Figs. 9, 8, 7 and 6.

The device forms a neat and attractive advertising novelty of a very puzzling nature, 20 which because of its cheapness and simplicity can be distributed free.

As shown in Figs. 3 and 4, the pliable member 16, is of such a length that when 25 one sheet is unfolded, the other is folded and lies against the unfolded member. In order to unfold both of the members, one must be detached.

It is of course understood that the rigid 30 members may be made in various sizes and that the pliable member 1 can be in the form of a chain, thong, or cord. Further, the members can be separated so that each loop 35 17 and 18 would encompass a plurality of detached members, as the ones marked 10, 11 and 12.

Having thus described my said invention,

what I claim as new and desire to secure by United States Letters Patent is:

A puzzle comprising a pliable member 40 provided at its ends with loops which are separated from each other by an intermediate portion of a predetermined length, a sheet capable of being folded upon itself several times each folded section having an 45 aperture within each end, said apertures registering when said sheet is folded, one of said loops being drawn through all the apertures within one end of said sheet, the remaining end of said pliable member then 50 being passed through said loop, and then continued through all of the openings within the other end of said sheet and a second sheet capable of being folded upon itself 55 several times each folded section having an aperture within each end said apertures registering when said sheet is folded the remaining loop of said pliable member being drawn through all the apertures within one end of said last mentioned sheet the opposite 60 end of said pliable member being passed through the remaining apertures and through said last mentioned loop, the intermediate portion of said pliable member being of such a length that when one of said 65 members is unfolded, the other is folded and held to the unfolded member, as and in the manner set forth.

In testimony whereof I affix my signature, in presence of two witnesses.

AUGUST CELUS.

Witnesses:

J. A. AUSTIN,
A. H. STEELE.
